UNITED STATES PATENT OFFICE.

BURTON H. BROMLEY, OF LOS ANGELES, CALIFORNIA, ASSIGNOR TO PRATT & WARNER, OF LOS ANGELES, CALIFORNIA, A FIRM COMPOSED OF O. V. PRATT AND F. S. WARNER.

IRONING-BOARD SUPPORT.

Application filed December 11, 1923. Serial No. 679,956.

This invention relates to supports for ironing boards.

The general object of the invention is to provide an improved collapsible support for a folding ironing board.

One of the specific objects of the invention is to provide a folding support for an ironing board which may be collapsed to allow the folding of the ironing board and which when in use supports the ironing board firmly.

Another object of the invention is to provide an ironing board support which may be collapsed against the board in one position and in another position may be moved to supporting position; the support having means for holding it in either position.

An additional object of the invention is to provide a bent wire support for an ironing board having a projection thereon which engages the ironing board to hold the support in operative or inoperative position.

Other objects of the invention will be apparent from the following description taken in connection with the accompanying drawings wherein Fig. 1 is a perspective view of an ironing board provided with my invention; Fig. 2 is a section through the ironing board showing the support in elevation; Fig. 3 is a perspective view of the under side of an ironing board having my support secured thereto; Fig. 4 is an elevation showing the ironing board support in folded position and Fig. 5 is a perspective view of a portion of the support showing the manner in which the loop is formed.

Referring to the drawing by reference characters, I have shown at 10 a casing for a holding ironing board, the casing is indicated as provided with an upper door 11 and with a lower door 12. The lower door is hinged to the casing at one end and at the upper end is hinged as at 14 to a supporting member 15. As shown in the drawings the supporting member 15 is a large ironing board although it can be understood that this member may be a table or other support. Mounted on a dowel 16 I show a short ironing board 17. This ironing board may be of a type known as a sleeve board.

In order to support the sleeve board when it is spaced above the large board 15 I show a supporting member 20. The supporting member 20 comprises a substantially U-

shaped member having a base 21 and having 55 upwardly extending legs 22. Each of the legs 22 is provided with an inturned portion 24 which is shown as fitted in a slot 25 in the sleeve board 17.

Instead of the single slot 25 I may provide 60 a short slot adjacent each end of the board to receive the projections 24. In one of the legs 20 I show a loop 26. This loop is so arranged that it provides a flat upper surface 27 which is preferably spaced from the 65 portion 24 a distance slightly greater than the distance from the bottom of the slot 25 to the bottom 28 of the sleeve board 17. The legs 22 of the support 21 are shown as spaced apart a distance somewhat greater 70 than the width of the board 17.

The support 21 is preferably made of resilient wire and in the position shown in Fig. 2 the support is arranged to hold the sleeve board in operative position with the 75 loop 26 engaging the under side of the board 27 and preventing swinging movement of the support 20. When it is desired to fold the sleeve board within the casing the support 20 is moved to the dotted line 80 position shown in Fig. 2 and then the leg having the loop 26 thereon is sprung outwardly as shown in dotted lines and the member 20 is swung on the portions 24 until the base 21 thereof lies adjacent the under side of the sleeve board as shown in 85 Fig. 4. In this position the inner face 30 of the loop 26 engages the adjacent edge of the board 17 and so holds the support in the position shown in Fig. 4.

When the operator wishes to move the support to operative position from the position shown in Fig. 4 the support is moved until the legs are at right angles to the ironing board. This being done, the support is moved laterally until the loop 26 engages beneath the ironing board.

From the foregoing description it will be apparent that I have invented an improved support for a pivoted member which can be 100 economically made and which is very effective in use. I wish it to be understood that the use of my support is not limited to the specific application shown but may be used wherever such a device is desirable.

I claim:

1. In combination with an ironing board, a strip of wire bent to form a U-shaped sup-

port, said ironing board having a hole in each side thereof and said support having its ends bent and inserted in said holes, and means integral with one leg of said support for engaging the lower side of the ironing board to hold the support at an angle to the ironing board.

2. In combination with an ironing board, a support, said support comprising a strip of wire bent to a U-shape and having the ends of each leg of the U bent at right angles to the leg on which it is arranged, said ironing board having a hole at each side thereof and said right angled portions being fitted in said holes, one leg of said U having an offset horizontal loop, said offset loop being spaced from said right angled portion and extending laterally thereof whereby it may engage said ironing board to hold said support at right angles to the ironing board.

3. The combination of an ironing board

and a support said support comprising a U-shaped strip of metal, means to pivotally mount the support on the ironing board, a horizontally extending loop formed in one leg of said U, said loop being adapted to lie beneath and spaced from the lower surface of said ironing board.

4. An ironing board support comprising a single strip of metal bent to form a U-shaped support, the free ends of the legs of the support being inturned for pivotal engagement with the board, a horizontally extending loop formed in one leg of said U, said loop being spaced from the inturned end and adapted to lie beneath the lower surface of the board to receive the ironing board between said loop and the inturned end.

In testimony whereof, I hereunto affix my signature.

BURTON H. BROMLEY.
